UNITED STATES PATENT OFFICE

146,982

DESIGN FOR A COMBINED LUGGAGE RACK AND LIGHT FIXTURE

Leonard R. Phillips, Teaneck, N. J., assignor to
Anemostat Corporation of America, New York,
N. Y., a corporation of Delaware

Application December 4, 1945, Serial No. 124,340

Term of patent 7 years

(Cl. D66—2)

To all whom it may concern:

Be it known that I, Leonard R. Phillips, a citizen of the United States, residing at Teaneck, in the county of Bergen and State of New Jersey, have invented a new, original, and ornamental Design for a Combined Luggage Rack and Light Fixture, of which the following is a specification, reference being had to the accompanying drawing, forming a part thereof.

Figure 1 is a perspective view of a combined luggage rack and light fixture showing my new design.

Figure 2 is a cross section thereof.

The design forming the subject matter of the present invention is for a combination luggage

rack and light fixture of arbitrary over-all length.

I claim:

The ornamental design for a combined luggage rack and light fixture, substantially as shown and described.

LEONARD R. PHILLIPS.
